CLAIM

The ornamental design for a swing, as shown and described.

DESCRIPTION

FIG. 1 is a front elevational view of a swing showing our new design;

FIG. 2 is a right side elevational view thereof, the left side being a mirror image thereof;

FIG. 3 is a rear elevational view thereof;

FIG. 4 is a top plan view thereof; and,

FIG. 5 is a bottom plan view.

The cords in the figures are shown broken away to indicate indeterminate length.

FIG. 1

FIG. 2

FIG. 3

FIG. 4

FIG. 5
